UNITED STATES PATENT OFFICE.

ALEXIS SAKOVITCH, OF NEW YORK, N. Y., ASSIGNOR TO MICHAEL WHITE, OF WINNIPEG, CANADA.

FAN.

No. 873,460.

Specification of Letters Patent.

Patented Dec. 10, 1907.

Application filed April 22, 1907, Serial No. 369,665.

To all whom it may concern:

Be it known that I, ALEXIS SAKOVITCH, subject of the Czar of Russia, residing at No. 528 East Eleventh street, New York city, 5 New York, have invented new and useful Improvements in Fans, of which the following is a specification.

My present invention relates to improvements in fans for hand or toilet use and the 10 object of the invention is to provide a simple form of rotary fan which may be easily manipulated to produce a strong breeze, and which may be readily folded into compact space when not in use.

15 The invention is included in the accompanying drawings, in which,—

Figure 1 is a side elevation. Fig. 2 is a plan view. Fig. 3 is a side elevation of the fan after folding. Fig. 4 is an end view.

20 Referring by reference characters to these drawings, the numeral 1 designates a block or element in which is rotatably and slidably mounted a shaft or spindle 2 which carries at its outer end the fan blades as shown. To 25 the block on opposite sides are pivotally connected the arms 3 which are normally forced apart by the spring 4 which is preferably formed of wire having divided coils 4^a located on opposite sides of the spindle, the ends of 30 the spring being inserted in openings in the arms.

A spiral spring 5 encircling the spindle has one end connected thereto and its other end connected to the block 1. A flexible cord 6 35 is connected to each arm and carried inward and wound around the spindle, and the relative arrangement of spiral spring and cord or cords is such that when the arms are drawn together by the grasp of the hand the spiral 40 spring rotates the spindle and fan in one direction, while the relaxing of the grasp upon the arms allows them to be forced apart by the spring 4 and causes the cords to unwind from the spindle and rotate it in the opposite 45 direction against the tension of the spiral spring. The spindle carries at its outer end a rigidly attached frame, preferably in the shape of a ring 7, which is connected with the end of the spindle by radial arms 7^a and to 50 this ring are pivotally connected a plurality of blade carrying arms 8. The blade carrying arms preferably have forked inner ends 8^a, the pivotal connection being effected by passing the ring which is round in cross section directly through openings in the forked

ends, though of course any form of pivotal connection suitable for the purpose may be adopted. The arms 8 are provided with upwardly turned V-shaped outer ends 8^b as shown and to these arms are pivotally secured the fan blades 9, the pivotal connection being effected by lugs 9^a and pivot pins or rods 9^b. By this arrangement it will be seen that as the fan wheel is rotated in one direction the fan blades will be held by the 60 air pressure inclined in one direction and on the reverse movement will be held inclined in the opposite direction with the result that notwithstanding alternate rotary motion, a current of air will always be forced in the 65 same direction.

It is desirable that a device of this character should be capable of being folded in a small compass, and in order to accomplish this the spindle is made longitudinally movable through the journal block as before described. A second ring 10 is located beneath the first ring and has a collar or sleeve 11 slidingly embracing the spindle. It is normally forced away from the first ring by 70 a helical spring 12 encircling the spindle. Each of the blade carrying arms is connected to a ring 10 by a link 13. The spindle is provided with a knob 14 by which it may be moved longitudinally as the grasping handles are forced together until finally the said 75 knob engages over the ends of the handles and holds them together. In this position the blade carrying arms will then have been swung upon the inner ring as a pivot until 80 they lie close together as shown in Fig. 3. The arms may be held together against accidental displacement by a retaining device, such as 15.

Having thus described my invention, what 85 I claim is:

1. A toilet or hand fan comprising a rotary spindle, reversible fan blades carried thereby, hand gripped levers, and means whereby the movement of said levers to and from each 90 other rotates said spindle in opposite directions, substantially as described.
2. In combination, a spindle carrying element, a spindle rotatably mounted therein, hand operated means for rotating said 95 spindle in opposite directions, automatically reversing blades carried by said spindle, and means for folding said blades, substantially as described.
3. In combination, the spindle carrier, a 100

spindle rotatable and longitudinally movable therein, hand levers pivotally connected to said spindle carrier, means whereby the opening and closing of said hand levers oscillate the said spindle, fan blade carrying arms pivotally connected with the spindle, and blades pivotally carried by said arms, substantially as described.

4. In combination, a spindle carrying element, a spindle journaled therein, a pair of arms pivotally connected to said spindle carrying element, a spring tending to force said arms apart, a flexible device wound upon the spindle and connected to the arms and operating upon the separation of the arms to rotate the spindle in one direction, a spring interposed between the spindle and spindle carrier tending to rotate the spindle in the

opposite direction, and automatically reversing fan blades carried by the spindle, substantially as described. 20

5. In combination, a spindle carrier, a spindle rotatably mounted therein, and means for rotating the spindle, a ring fixedly attached to the spindle, fan carrying blades 25 pivotally connected to said ring, a second ring movable on the spindle, and links connecting the blade carrying arms with said ring, substantially as described.

In testimony whereof I have signed my 30 name to this specification in the presence of two subscribing witnesses.

ALEXIS SAKOVITCH.
